UNITED STATES PATENT OFFICE.

GEORGE C. LYNCH, OF NEW YORK, N. Y.

DESIGN FOR A LAMP-SHADE.

48,228.

Specification for Design.

Patented Nov. 30, 1915.

Application filed July 1, 1915. Serial No. 37,600. Term of patent 3½ years.

To all whom it may concern:

Be it known that I, GEORGE C. LYNCH, a citizen of the United States, and a resident of the city of New York, borough of Manhattan, in the county and State of New York, have invented a new, original, and ornamental Design for Lamp-Shades.

The figure is a side elevation of a shade for a lamp, showing my new design.

I claim:

The ornamental design for lamp shade as shown.

GEORGE C. LYNCH.

Witnesses:

S. J. GENSLER,
E. F. GORDON.
